UNITED STATES PATENT OFFICE.

JAMES THEODORE WRIGHT, OF METUCHEN, NEW JERSEY.

ANTITWISTING MECHANISM.

1,333,147.

Specification of Letters Patent. Patented Mar. 9, 1920.

Application filed February 27, 1919. Serial No. 279,652.

To all whom it may concern:

Be it known that I, JAMES T. WRIGHT, a citizen of the United States, and resident of Metuchen, in the county of Middlesex and State of New Jersey, have invented certain new and useful Improvements in Antitwisting Mechanism, of which the following is a specification.

In Letters Patent of the United States No. 1,178,566 dated April 11, 1916, is described an apparatus for progressively removing the twist from a tape, cord, wire or other analogous stock as it is drawn from a roll; and particularly an apparatus for operating upon rolled flat goods, such as tape, whereby the out-drawn stock is intermittently turned in opposition to the direction of the twist so as to leave the progressing material flat and capable of being efficiently worked.

In the form of invention illustrated in said Letters Patent there is provided a rotatable support for a roll or rolls of stock; an electric motor operatively connected with the support; and an oscillatory guide for the stock as it runs from the roll or rolls; said guide being operatively associated with the contacts of a normally-open electric circuit in which the electric motor is included, whereby when the guide is partially turned by the increased tension on the stock, resulting from twisting, the circuit is closed and the motor, being energized, effects the partial rotation of the support and the roll in a direction to untwist the stock, and whereby when the stock is thus untwisted and is under normal tension the guide is retracted to break the electric circuit, and temporarily deenergize the motor until the tension on the tape is again increased; and so on in alternation.

The direct making and breaking of the main electric circuit by the varying tension on the tape was relatively slow and hence, due to the high voltage, the contacts were soon destroyed. To overcome this defect is the object of my present invention, and accordingly I provide, in addition to the main circuit in which the motor is included, a supplementary circuit in which the guide-controlled contacts, an electric battery, and an electro-magnetic contact device for the main circuit are included, which device is inter-

mittently energized and deenergized through the operation of the tape controlled guide contacts and is adapted to make and break the main electric circuit and thus determine the active and idle conditions of the motor; all as will be hereinafter described and claimed.

In the drawings—

Figure 1 is a side elevation, partly diagrammatic, of an anti-twisting machine equipped with circuit making and breaking devices embodying the preferred form of my invention.

Fig. 2 is a plan of the said devices.

Fig. 3 is a side elevation of the same.

Fig. 4 is a transverse section as on the line 4—4 of Fig. 2.

Referring to the drawings, 10 designates a rotary support comprising a turn-table having a vertical shaft which is stepped in a bearing in a base 11. A cylindrical casing 12 borne by the turn-table is adapted to contain a roll or rolls of material, such as flat tape 13, to be operated upon. An electric motor 14 is operatively connected with the turn-table and is designed to rotate the latter at intervals in order to remove the twist progressively from the stock as it is being withdrawn from the roll or rolls. In the present instance a belt and pulley connection is illustrated between the motor shaft and the shaft of the turn-table. The mains of the electric circuit for the motor are indicated at 15.

Supported a suitable distance above the turn-table is a contact-controlling device for a supplemental electric circuit 16, having an independent source of electric supply, such, for example, as the battery 16'. This device comprises a guide-element about which the tape passes as rapidly as it is withdrawn from the roll or rolls, which guide element in the present instance is constituted by a horizontal tape-supporting member 17 having spaced end heads 18 adapted to prevent edgewise displacement of the tape 13. The member 17 is provided with an angular overhanging portion 17' which is formed on or secured to the lower end of a depending rod 19 having at its upper end a yoke portion supporting a horizontal bifurcated plate 20 (of non-conducting material) which is pivoted, as at 21, to an arm 22 extending from a

bracket 23, affixed to a suitably-disposed shelf 24, whereby said member when under pressure will turn on a vertical axis. Hence when the tension on the tape as it passes upon and over the member 17 is increased by the twisting of the tape, said member and its associated parts are partially rotated, and when the increased tension is removed they are returned to their normal position.

10 The spaced apart legs 20' of the plate 20 embrace an upstanding vibratory contact member 25 which is pivotally supported at its lower end in an insulating block 26 on the bracket 23 and is included in the supplementary electric circuit. In this circuit is also included a contact plate 27 which is secured to an insulating block 28 on the bracket and is arranged in the path of the upper end of the contact member 25, where-

15 by when the latter is oscillated by the varying action of the running tape on the supporting member 17 as above described, such circuit is broken and completed at intervals. In the supplemental circuit is also included

20 an electro-magnet 29 which is supported on the shelf 24. The armature 30 of the magnet is formed on or secured to the longer arm of a lever 31 which is fulcrumed on a post 32 rising from the base 33 of the electro-

25 magnet. The shorter arm of this lever is depressed in opposition to the action of the magnet by a suitably-disposed spring 34; the upward throw of the longer arm of the lever being determined by a stop-screw 35 mounted on a post 36 on the base 33. The longer arm of the lever is provided with a set-screw 37 having an insulating tip 37' which bears upon one of two normally separated contact plates 38, 39 respectively,

30 which are included in the main electric circuit, whereby, during the operation of the armature and the lever through the making and the breaking of the supplemental circuit by the contacts 25, 27, as previously described, the main circuit is completed and broken. The contact plates 38, 39 are mounted on an insulating block 40 on the base 33.

When the running tape as it passes over the guide-element is under normal tension both the main and supplemental circuits are broken, and therefore the motor is idle; but when the tension of such tape is increased by the twisting of the portion between the roll or rolls and the guide-element the latter is partially rotated to cause one of the limbs of the plate 20 to swing the vibratory contact member 25 against the complementary contact member 27 of the supplemental circuit, thus completing the latter circuit, energizing the magnet, and, perforce, quickly closing the contacts of the main circuit in which the motor is included. The motor, being energized, rotates the casing 12 and

45 the tape in a direction to remove the twist

from the running tape, whereupon the normal tension on the tape effects the return of the guide-element to its previous condition, thereby moving the plate 20 in a manner to swing the contact member 25 from the member 27 and break the supplemental circuit. This done, the electro-magnet, being deenergized, instantly releases the armature and breaks the main circuit, thus de-energizing the motor and permitting the normal travel of the tape until the tension on the latter is increased, and so on in alternation.

From the foregoing construction and operation it will be seen that the making and breaking of the main circuit are each quickly effected and that the otherwise liability of burning out the contacts for such circuit is obviated.

I do not limit myself to the specific details of construction herein shown and described, as the mechanism may be variously modified within the spirit of my invention and the scope of the appended claims.

I claim:

1. The combination of a rotatable stock support, an electric motor, operative connection between said support and motor, a main electric circuit in which said motor is included, an electro-magnet for intermittently closing and opening said circuit, a supplemental electric circuit in which said electro-magnet is included, and means including a movable stock guide for intermittently opening and closing said latter circuit.

2. The combination of a rotatable stock support, an electric motor, operative connection between said support and motor, a main electric circuit in which said motor is included, an electro-magnet for intermittently closing and opening said circuit, a suspended movable guide-member over which the stock runs, a device mounted to turn with the said member, a contact adapted to be actuated by said device, a second contact in the path of the first contact, and a supplemental electric circuit including the said contacts and electro-magnet.

3. The combination of a rotatable stock support, an electric motor, operative connection between said support and motor, a main electric circuit in which said motor is included, an electro-magnet for intermittently closing and opening said circuit, a pivotally-suspended rod having a bifurcated device at its upper end and a stock guide at its lower end, a vibratory contact embraced by said device, a second contact in the path of the vibratory contact, and a supplemental electric circuit including the said contacts and the electro-magnet.

4. The combination of a rotatable stock support, an electric motor, operative connection between said support and motor, a main electric circuit in which said motor and two

contacts are included, an electro-magnet, a lever carrying the armature of the magnet, said lever adapted to make and break the said contacts, a pivotally-suspended rod having a bifurcated device at its upper end and a stock guide at its lower end, a vibratory contact embraced by said device, a second

contact in the path of the vibratory contact, and a supplemental electric circuit including the electro-magnet and the last-named contacts. 10

Signed at New York, in the State of New York, this 13th day of February, A. D. 1919.

JAMES THEODORE WRIGHT.
